(57) **CLAIM**

The ornamental design for a kneeling pad, as shown and described.

DESCRIPTION

FIG. 1 is a perspective view of an embodiment of a kneeling pad showing my new design;

FIG. 2 is a front view thereof;

FIG. 3 is a back view thereof;

FIG. 4 is a top view thereof;

FIG. 5 is a bottom view thereof;

FIG. 6 is a right side view thereof; and

FIG. 7 is a left side view thereof;

FIG. 8 is a perspective view of an alternative embodiment of the kneeling pad;

FIG. 9 is a front view thereof;

FIG. 10 is a back view thereof;

FIG. 11 is a top view thereof;

FIG. 12 is a bottom view thereof;

FIG. 13 is a right side view thereof; and

FIG. 14 is a left side view thereof;

FIG. 15 is a perspective view of another embodiment of the kneeling pad;

FIG. 16 is a front view thereof;

FIG. 17 is a back view thereof;

FIG. 18 is a top view thereof;

FIG. 19 is a bottom view thereof;

FIG. 20 is a right side view thereof; and

FIG. 21 is a left side view thereof;

FIG. 22 is a perspective view of another embodiment of the kneeling pad;

FIG. 23 is a front view thereof;

FIG. 24 is a back view thereof;

FIG. 25 is a top view thereof;

FIG. 26 is a bottom view thereof;

FIG. 27 is a right side view thereof; and,

FIG. 28 is a left side view thereof.

The broken lines shown in the drawings represent portions of the kneeling pad that form no part of the claimed design.
